U.S. Appl. No. 14/977,131, filed Dec. 7, 2016, Office Action.
(Continued)*Primary Examiner* — Lakiya G Rogers*Assistant Examiner* — Carissa C Fitts(74) *Attorney, Agent, or Firm* — Workman Nydegger(57) **CLAIM**

The ornamental design for a lantern, as shown and described.

DESCRIPTION

FIG. 1 is a front perspective view of a lantern according to the present invention;

FIG. 2 is a rear perspective view of the lantern of FIG. 1;

FIG. 3 is a front view of the lantern of FIG. 1;

FIG. 4 is a rear view of the lantern of FIG. 1;

FIG. 5 is a first side view of the lantern of FIG. 1;

FIG. 6 is a second, opposite side view of the lantern of FIG. 1;

FIG. 7 is a top view of the lantern of FIG. 1; and,

FIG. 8 is a bottom view of the lantern of FIG. 1.

The broken lines show portions of the lantern not claimed and form no part of the claimed design.

1 Claim, 7 Drawing Sheets(56)
